UNITED STATES PATENT OFFICE.

WILLIAM G. LATIMER, OF DETROIT, MICHIGAN, ASSIGNOR TO THE LATIMER CASH REGISTER COMPANY, OF SAME PLACE.

CASH-REGISTER.

SPECIFICATION forming part of Letters Patent No. 435,067, dated August 26, 1890.

Application filed April 3, 1890. Serial No. 346,482. (No model.)

To all whom it may concern:

Be it known that I, WILLIAM G. LATIMER, a citizen of the United States, residing at Detroit, in the county of Wayne and State of Michigan, have invented certain new and useful Improvements in Cash-Registers, of which the following is a specification, reference being had therein to the accompanying drawings.

This invention relates to new and useful improvements in a locking device for the keys of cash-registers; and the invention consists in the arrangement of a sliding bar provided with slots in which arms upon the keys are adapted to engage, said slots being variously inclined, whereby the bar in which said slots are formed is given a different movement by the operation of each of said keys, and whereby the simultaneous operation of more than one key is prevented, all as more fully hereinafter described.

In the drawings which accompany this specification, Figure 1 is a section through a cash-register, showing the keys only, the tablet-rods and registering mechanism of which may be of any desired construction. Fig. 2 is a cross-section on line $\alpha\alpha$ in Fig. 1. Fig. 3 is a similar section, showing the parts in position when operated.

Are the keys, which are journaled upon the shaft B, and which I preferably arrange in groups or banks of nine. These groups are preferably three in number—one for cents, one for dimes, and one for dollars; but I show herein but one group, as that is all that is necessary for the explanation of my improvement, as the locking device for each is independent of the other groups.

C is the shaft or bar secured in the frame of the machine transversely, extending across the keys and supported in any suitable manner. Upon this shaft is slidably secured the bar D. By means of the upwardly-extended arms E between these arms is stationarily secured on the shaft C the block F, and between this block and the arms E upon both sides are sleeved the springs G, which by their tension tends to hold the bar normally in position, as shown in Fig. 2. This bar is provided on its under side with a series of slots α , which I preferably arrange as shown in Fig. 2, with

the series b to the left of the center, slanting toward the center, and the series c to the right of the center, likewise slanting toward the center, while the central slot d is vertical.

e are arms secured upon the keys, each arm carrying a rearwardly-projecting pin f , which is arranged directly opposite the lower end of the corresponding slot in the bar D.

The parts being thus constructed and arranged upon the operation of a key—say, for instance, the key lettered H—the bar e will be carried up and with it the pin f , which will enter the lower end of the left-hand slot, striking against the inclined slot g thereof. The continued upward movement of this pin in the slot will throw the bar D to one side, acting against the tension of the spring. When the pin has passed to the end in the slot, the spaces h will be opposite the pins, thereby acting as a stop. Should the central key i be operated it will enter the vertical slot d and prevent the necessary movement of the bar, which is required in the operation of any of the other keys. Should two keys be operated simultaneously—one in each of the groups b c —the reverse action of the inclined slots would prevent the movement of the bar in either direction, and thereby prevent such operation of two such keys. The operation of two keys in either one of the groups would be prevented by the difference in incline of the slots in said groups. Unless the key is withdrawn the spring returns the bar to its normal position ready for the operation of another key.

It is evident that the arms upon the keys may be omitted and the upper edges of the keys themselves enter the slots in the sliding bar.

What I claim as my invention is—

1. In a cash-register, the combination, with the keys, of a movable bar arranged above the same and provided with a series of differently-inclined slots and a spring designed to return said bar to its normal position, substantially as described.

2. In a cash-register, the combination, with the keys, of a locking-bar for preventing the simultaneous operation of two or more keys, consisting of a movable bar provided with a

series of differently-inclined slots or apertures adapted to be traversed by a part of the key to move said bar upon the operation of a key, substantially as described.

5 3. In a cash-register, the combination, with the keys, of a locking-bar for preventing the simultaneous operation of two or more keys, consisting of a movable bar provided with a series of differently-inclined slots or apertures adapted to be traversed by the key or an arm

thereof and a spring to return said bar to its normal position, substantially as described.

In testimony whereof I affix my signature, in presence of two witnesses, this 28th day of January, 1890.

WILLIAM G. LATIMER.
